UNITED STATES PATENT OFFICE.

JAMES M. DAYTON, OF TORRINGTON, CONNECTICUT, ASSIGNOR TO STANDARD COMPANY, OF TORRINGTON, CONNECTICUT, A CORPORATION OF MAINE.

IGNITER FOR INTERNAL-COMBUSTION ENGINES.

1,249,909.

Specification of Letters Patent. Patented Dec. 11, 1917.

Application filed September 26, 1914. Serial No. 863,676.

To all whom it may concern:

Be it known that I, JAMES M. DAYTON, a citizen of the United States, residing at Torrington, in the county of Litchfield and State of Connecticut, have invented certain new and useful Improvements in Igniters for Internal-Combustion Engines, of which the following is a specification, reference being had to the accompanying drawing.

10 My invention relates to electric igniters for internal combustion engines, and particularly to igniters of the make-and-break type, and consists of an improved construction of the insulated electrode whereby same may be more thoroughly and permanently insulated from the body of the igniter than heretofore. A further object is to so construct this electrode, that it may be readily removed and replaced in the igniter casting 20 without disturbing the insulation.

Another object is to provide an insulated electrode of unit construction in which it is impossible to pull the insulated stem member out of the insulation by tightening up on 25 the clamping nuts.

Figure 1 is a sectional view of an igniter casting, showing my improved electrode in place, and Fig. 2, a view partly in section of a complete igniter embodying the improved 30 electrode. Like figures of reference denote the same parts wherever they are shown.

For the sake of illustration, a well known form of make-and-break igniter is shown, but as my invention may be used with any 35 form of make-and-break igniter, I do not limit myself to the precise form herein shown and described.

Make-and-break igniters are usually assembled by the engine manufacturer, and as 40 a rule such manufacturers are not skilled in the assembly of electrical appliances, and therefore many igniters are not properly and thoroughly insulated. Often asbestos and shellac, or common cut mica, have been employed for surrounding the insulated member 45 of the igniter, which insulation is simply placed around the electrode stem, which is forced into a hole in the body of the igniter casting. This construction has resulted in short circuits and other trouble, 50 due principally to the disintegration of the insulation, owing to the excessive heat in the combustion chamber, and to the lodgment of soot on the exposed edges of the mica washers.

In the construction I employ, it is possible for the insulated member of the igniter to be assembled by those familiar with handling insulation, and this part can be sold to the engine manufacturer complete ready to 60 mount in the igniter casting like an ordinary spark plug; then the only work the engine manufacturer must do is purely of a mechanical character, with the result that the igniter is properly insulated, and so arranged that the insulated member may be readily removed or replaced in the igniter casting without disturbing the insulation or without the necessity for any particular electrical knowledge.

70 My improved construction of the insulated member of the igniter consists of the electrode stem 1, which is tapered as shown, and which is incased in a tube 2, from which it is insulated, preferably by rolled sheets of 75 mica 3. This mica projects outwardly toward the contact end 11 of the stem, and presents a smooth unbroken surface upon which carbon and soot will not find ready lodgment. This is not the case if mica 80 washers were forced on the stem 1, as the edges of the mica enable oil or soot to find lodgment.

The outer end of 1 is threaded and provided with suitable clamp nuts 4 and 4', and 85 terminal 5. The igniter casting 6 is bored out to receive the tube 2, and is also provided with a recess 7 to accommodate the projecting end of the mica 3. The igniter flange or face 12 is slightly counterbored for the 90 washer 8 and the insulation 9, which parts support the outer end of stem 1.

95 It will be observed that the foregoing construction is such that by the removal of nuts 4 and 4', the stem 1 with its contact, is removable together with the tube 2 and insulation 3, from the igniter casting 6 as a unit, without disassembling the stem from the tube.

100 It will furthermore be observed that regardless of how tight the nuts 4 and 4' may be drawn, it is impossible to pull the taper stem 1 out of the tube 2 and thereby displace the insulation.

105 Furthermore, a gas-tight joint is obtained between the stem 1 and tube 2, and between the stem and tube as a unit, and the casting 6 by means of the gasket 13, and that tightening the clamp nuts not only tightens the tube 2 in the casting 6, but also draws taper 110

stem 1 into its insulation, thereby keeping a gas-tight joint.

This construction enables the unskilled to remove the insulated parts of a make-and-break igniter without in any way affecting the electric insulation or adjustment of the parts and obviates the necessity of the gas engine manufacturer doing any electrical testing on the igniter insulation.

10 The operation of the make-and-break igniter being well understood, I do not describe same, it being understood that my invention may be utilized in any form of igniter mechanism, having a movable member 10.

Having thus described my invention, I claim:

1. An igniter comprising a flanged body casting having an aperture in the body at 20 right angles to the flange, a tube in said aperture, a taper member in said tube, insulation between said tube and member, a stem projecting from said member through said flanged body and beyond the outer face 25 thereof, and means insulated from said body and carried by said stem whereby said tube, stem and insulation are clamped in said body as a unit, substantially as described.

2. An igniter comprising a flanged body 30 casting having an aperture in the body at right angles to the flange, tube in said aperture, taper member in said tube, insulation between said tube and member, stem projecting from said member through the 35 flanged body and beyond the outer face thereof, a recess in said flange surrounding said stem, and means carried by said stem and fitting said recess, whereby said stem is centrally located in said aperture, substantially as described.

3. An igniter comprising a body having a flange, an aperture part way through said body at right angles to the flange thereof, an aperture of lesser diameter than said first 45 mentioned aperture communicating and concentric therewith and completing an opening through said body, a tube in said first mentioned aperture, a tapered contact member in said tube projecting freely from 50 the ends thereof and from said second aperture, an insulation comprising rolled sheets of insulating material between said tube and member, said insulation projecting from both ends of said tube so as to present a free 55 surface parallel with the axis of said member.

4. An igniter comprising a flanged body, an aperture in the body at right angles to the flange said aperture extending part way

through the body, a second aperture concentric with said first aperture and communicating therewith but of lesser diameter, continuing through said body and forming with said first aperture an opening therethrough, a tube in said first aperture, a tapering member in said tube, insulation between said tube and member, a stem projecting from said member through said second aperture and beyond the outer face of said body and a removable contact point secured 70 to one end of said tapered member.

5. A make and break igniter including in combination, an igniter body, a movable electrode carried thereby, a fixed electrode carried by the igniter body and coöperating 75 with said movable electrode, said igniter body having an opening extending therethrough for said fixed electrode, a tube through which said fixed electrode extends, insulation in said tube forming a continuous 80 wall from end to end of this tube and projecting beyond the ends thereof, the stem of said electrode extending through the tube being tapered, said opening in the igniter body for the electrode having an enlarged 85 portion forming a seat for the tube, and means carried by the outer end of the stem of the electrode for clamping the tube against its seat in the igniter body.

6. A make and break igniter including in 90 combination, an igniter body, a movable electrode carried by said igniter body, a fixed electrode carried by said igniter body and coöperating with said movable electrode, said igniter body having an opening 95 extending therethrough for said fixed electrode, a tube through which the stem of the electrode extends, said stem being tapered, a sleeve of insulating material surrounding the stem of the electrode and located within 100 said tube and extending beyond the ends thereof, said opening having an enlarged portion forming a seat for the tube, a gasket between the ends of said tube and the seat, the stem of said electrode extending beyond 105 the outer face of the igniter body and having threads thereon, clamping means mounted on said stem for clamping the tube against the seat, and an insulating washer between said clamping means and the outer face of 110 said igniter body.

In testimony whereof I hereunto affix my signature in the presence of two witnesses.

JAMES M. DAYTON.
